(57) **CLAIM**

The ornamental design for a bag dispenser, as shown and described.

DESCRIPTION

FIG. 1 is a perspective view showing the front, top and right sides of the bag dispenser;

FIG. 2 is a front elevation view of the bag dispenser;

FIG. 3 is a right side elevation view of the bag dispenser, the left side elevation view being a mirror image thereof;

FIG. 4 is a rear elevation view of the bag dispenser;

FIG. 5 is a top plan view of the bag dispenser; and,

FIG. 6 is a bottom plan view of the bag dispenser.

The broken lines shown in the drawings represent portions of the bag dispenser that form no part of the claimed design.
